UNITED STATES PATENT OFFICE

ALFRED BURNS, OF EASTHAMPTON, MASSACHUSETTS, ASSIGNOR TO WEST BOYLSTON MANUFACTURING COMPANY, OF EASTHAMPTON, MASSACHUSETTS, A CORPORATION OF MASSACHUSETTS

METHOD OF MAKING PRINTED FABRICS

Application filed January 10, 1929. Serial No. 331,670.

This invention relates to the making of printed textile fabrics in which the design is printed on the warp prior to the drawing of the warp into the loom, and it has for 5 its general object to provide a novel method by which a one-piece fabric of substantially any desired width can be made from a single warp.

One familiar way of printing a warp (the 10 term "warp" in the textile art is commonly used as descriptive of a web of warp threads such as is drawn into a loom for the weaving operation) is by means of a printing machine through which the warp is carried and which 15 has printing rollers arranged to print the design on the warp as it passes through the machine.

For various reasons it is not considered practical to print a warp wider than about 20 fifty inches and in order to weave a one-piece fabric wider than this from printed warps it has been proposed to print two warps and then arrange them side by side and wind them onto a warp beam in this relation. In 25 doing this more or less difficulty is experienced in keeping the two warps properly matched so that when the wide fabric is woven from the combined warps the figure or design will be properly matched along the 30 line where the two warps meet.

The present invention provides a novel method by which a single warp may be printed on an ordinary warp printing machine, and then manipulated so as to form a warp 35 for a one-piece fabric of substantially any width.

One way of carrying out the invention is to arrange the number of ends required to make a one-piece fabric of the desired width 40 in the form of a warp which has a width such that it can be printed in the ordinary warp-printing machine designed for this purpose, and then to print on this warp a design which is distorted with relation to the final 45 design which is to appear on the woven fabric.

After the warp has thus been printed with the distorted design or pattern the ends or 50 threads comprising the warp are re-arranged with relation to each other so as to make a

warp of a width suitable for weaving a one-piece fabric of the desired width, during which operation the distorted design which has been printed on the warp threads is restored to its normal shape and appearance. 55 The warp in this condition is beamed and then drawn into the loom and a fabric woven therefrom in the usual way.

By means of this invention it is possible to print at one operation a single warp which 60 in its normal condition, that is, when it is beamed ready for the loom, is considerably wider than could be printed with any of the warp-printing machines now in common use.

In order to give an understanding of the 65 invention I have illustrated in the drawings more or less diagrammatically some of the steps involved in the method.

Fig. 1 is a diagrammatic view illustrating 70 a single warp which has been condensed transversely from its normal width and on which is printed the pattern in distorted shape, said figure showing said warp being restored to its normal width; and wound on a beam ready for the loom.

Fig. 2 is a side view of Fig. 1;

Fig. 3 illustrates the appearance of the 75 printed warp after it has been restored to its normal width and as it is ready to be drawn into the loom.

In the drawings 1 indicates a beam adapted 80 to receive a wide warp 2, that is, a warp which is considerably wider than it would be possible to print at one operation in any of the warp printing machines now in common use. This 85 beam might be either the warp beam of a wide loom or any beam adapted to receive a warp.

In carrying out my invention in accordance 90 with the method illustrated in the drawing I first form a warp of the desired number of ends to make a one-piece wide fabric and then I arrange these ends in closer relation than their normal relation in the wide fabric which is to be made, thereby to produce 95 a warp which is considerably narrower than the warp as it is to be drawn into the loom. In other words, the warp is condensed in a transverse direction to such dimensions that it can be readily passed through and printed by 100

any of the ordinary warp printing machines now in common use.

In printing this transversely condensed warp the pattern is printed thereon in distorted form. In other words, the printing element of the printer, whether in the form of rolls or in the form of a block, is so engraved or made that the design which is printed on the condensed warp is reduced in a direction transversely of the warp but not in a direction longitudinally of the warp. A warp having a design of this nature printed thereon is shown at 3 and is illustrated as being carried by a beam 4.

In order to illustrate this manner of printing the warp we will assume that the design which is to appear in the woven fabric comprises a series of circles 5 in the body of the warp and a border on each side comprising the V-shaped portions 6 connected by straight line portions 7. When this design is condensed transversely of the warp the circles 5 will appear as ellipses while the V-shaped portions 6 will still appear as V-shaped portions but of less height.

The printing element will be so designed as to print on the condensed warp the ellipses indicated at 8 and the distorted V-shaped portions indicated at 9 in Fig. 1. The figures 8, shown as ellipses in the illustrated embodiment of the invention, have the same dimension longitudinally of the warp as the circles 5 but their dimension transversely of the warp is, of course, less than the diameter of the circles. These ellipses thus represent circles distorted. Similarly, the V-shaped portions 9 of the transversely condensed warp 3 represent the V-shaped portions 6 distorted.

After the fabric is printed with this distorted pattern the threads or ends of the warp are then re-arranged so as to restore the pattern to its correct proportion and shape. In the illustrated embodiment of the invention this is accomplished by expanding the condensed warp 3 back to its normal width and then winding the warp when thus expanded onto the beam 1. As herein shown the warp in its condensed condition as shown at 3 is passed through suitable feed rolls 10 and then is carried through a comb or reed 11 which is so constructed as to give the ends of the warp their proper separation relative to each other. In other words, this comb or reed 11 is such as to maintain the warp at the desired width.

The normalized warp is then wound on the beam 1 which may be the warp beam of a loom or may be any other beam adapted to hold the warp. After the warp has been brought back into normal condition and has been wound on the beam 1, then it may be used for weaving a one-piece wide fabric in any usual way. The result is a wide one-piece fabric which is made from a single printed warp that has been printed on a warp-print-

ing machine which is incapable of handling a warp of the normal width of the warp 1.

Inasmuch as the completed wide fabric is made from a single warp which is printed at one operation all the difficulty of matching the pattern which is involved where the warp for the wide fabric is printed in two or more sections is obviated. Furthermore, since there is only one printed warp used in the wide fabric a considerable saving is effected in the printing operation over what is involved in making a wide fabric from two warps separately printed and then arranged side by side to produce the wide fabric.

A further advantage resulting from my improved method is the saving in the beaming operations. Where the entire warp for the wide fabric is handled as a single unit rather than in sections there is obviously a saving in the beaming operations as well as in other textile operations.

In its broadest aspect my invention includes the printing on a warp a pattern in distorted form and subsequently re-arranging the threads of the warp to present the pattern in correct or non-distorted form and then beaming the warp with the threads in their re-arranged normal condition with the pattern therein undistorted or normal.

While I have herein illustrated this method as being carried out by printing on a warp a pattern which is distorted in a direction transversely of the warp but not longitudinally of the warp and then expanding the warp transversely to bring the pattern back to its normal condition before the warp is finally wound on the loom beam, yet I do not wish to be limited to this particular aspect of the invention as I consider the invention broad enough to cover the idea of printing a distorted pattern on a warp and then re-arranging the threads of the warp in any way necessary to present the design or pattern in non-distorted or normal condition and the subsequently weaving a fabric from the warp with the normalized pattern thereon.

The invention is adapted for use in making one-piece bedspreads, one-piece table covers, one-piece wide portières, draperies or the like, or any other wide one-piece fabric.

I claim:

1. The steps in the process of making a printed fabric which consist in printing on the warp a design which is distorted in a direction transversely of the warp by having shortened transverse dimensions, re-arranging the ends of the warp so as to restore said design to its normal transverse dimension and then weaving a fabric from said warp.

2. The steps in the method of weaving a printed fabric which consist in printing on a warp a pattern which is shorter in a direction transversely of the warp than the normal pattern desired for the fabric, expanding the warp transversely to bring the pattern back

to normal shape and then weaving a fabric from the expanded warp.

3. The steps in the process of weaving a printed fabric which consist in arranging a given number of warp threads in web form and in closer relation than is desired in the completed fabric, printing on said web a design which is distorted in a direction transversely of the web, expanding the web transversely to bring the design back to normal shape and then weaving a fabric from said web.

10 4. The steps in the method of making a printed fabric which consist in printing on a warp a pattern in distorted form, rearranging the ends of the warp relative to each other to present the pattern in correct form, winding the rearranged ends onto a warp beam and subsequently weaving a fabric from said warp in any usual way.

15 5. The steps in the method of weaving a one-piece printed fabric which consists in providing a printing element which is constructed to print a design that is distorted with relation to the design desired in the completed fabric, printing a warp with said printing element, rearranging the threads or ends of the warp relative to each other so as to present the design in its normal shape, beaming the warp 20 25 30 after the ends have been thus rearranged and then weaving a fabric from the warp in usual way.

In testimony whereof, I have signed my name to this specification.
